UNITED STATES PATENT OFFICE.

JOHN LOGIE BAIRD, OF LONDON, ENGLAND, ASSIGNOR TO TELEVISION LIMITED, OF LONDON, ENGLAND, A BRITISH COMPANY.

LIGHT-SENSITIVE ELECTRIC DEVICE.

Application filed May 8, 1928, Serial No. 276,162, and in Great Britain May 7, 1927.

This invention is for improvements in or relating to light-sensitive electric devices of the type in which light-sensitive materials such as selenium, thallium sulphide, carbon and so forth are used, these being substances which change their electrical resistance when exposed to radiant energy; the object of the invention is to provide a construction whereby the time-lag of the response of the device is reduced or eliminated, and in some instances the device is rendered more sensitive.

The invention accordingly comprises a light-sensitive cell wherein the light-sensitive substance is in the form of a thin film which provides the maximum active area with the minimum weight and heat capacity, so that any response of the material due to change in temperature may, where suitable, be utilized in addition to the photoelectric effect.

The thin film aforesaid of the light-sensitive substance, may, according to another feature of this invention, be made so thin that it cannot support itself, and in this case the film is disposed on an insulating support which is itself of the minimum thickness necessary to provide the mechanical support for the film. With this arrangement, the thin film may conveniently be obtained by sputtering it on the supporting element.

The electrical resistance of selenium and other light-sensitive substances varies with its temperature, and the temperature coefficient itself varies, being positive over some ranges of temperature and negative over others: this variation is independent of the resistance variation due to the action of light. The present invention therefore comprises further the combination with a light-sensitive cell, of means for controlling its temperature whereby it may be operated in circumstances in which the thermal effect is additive to the optical effect when radiation falls on the cell, and the sensitivity is thereby considerably increased.

This invention also comprises the combination with a light-sensitive cell, its circuits and amplifying devices, of means for controlling the temperature of some or all of these parts in order that parasitic currents in the conductors may be minimized by maintaining them at a low temperature.

This invention also comprises a construction of light-sensitive cell in which a sub-

stantially closed chamber has a light-sensitive substance disposed in the form of a thin coating on its inner surface, and preferably extending all over that surface: this chamber has an opening through which radiation can enter it to impinge on the light-sensitive substance and be entirely absorbed thereby.

According to another feature of this invention a light-sensitive cell may be constituted by a light-sensitive fluid or liquid in the form of a thin layer enclosed between two transparent plates or one opaque and one transparent plate.

In the accompanying drawings, which illustrate this invention diagrammatically—

Figure 1 is a perspective view showing a thin film of light-sensitive material mounted on a supporting element;

Figure 2 shows an alternative construction in which the light-sensitive element is self-supporting;

Figure 3 is a sectional view showing diagrammatically the cell adapted for temperature control; and

Figures 4 to 8 show diagrammatically various constructions of light-sensitive cell.

In the construction illustrated in Figure 1, a very thin sheet of mica or other insulating material 10 has a thin film of selenium sputtered on to it, for instance, by means of an electric arc, using the material selenium as one electrode. Electrical contacts are provided at the two ends of the strip in any convenient manner, as for example by spring clips 12. The mica or other insulating support is made of the minimum thickness which will provide sufficient mechanical strength and rigidity, and the film of selenium is so thin that it would not be mechanically self-supporting.

In the construction illustrated in Figure 2, a single large crystal of selenium may have conductors attached to its opposite ends 13, 14, and the intervening material is ground away as at 15 so as to make it as thin as is consistent with the necessary mechanical strength.

In both these constructions the active part of the selenium is of the minimum thickness so that the exposed area is large compared with the mass and heat-capacity. It is preferable that the terminal connections should also be of small heat-capacity, but as the conductivity of a very thin layer or

strip is but small, the heat-capacity of the terminals is not of such great importance.

Figure 3 illustrates diagrammatically a light-sensitive cell in which provision is made for regulating the temperature. It comprises a light-sensitive element 16 which may for example be similar to that illustrated in Figure 1, and it is enclosed in a double-walled chamber 17. A glass, quartz or other transparent window 18 is provided in this chamber to permit the entry of the radiant energy which is to act on the light-sensitive material. The space between the double walls may be used for circulating a cooling or heating fluid through pipe-connections 19, or alternatively or additionally a suitable resistance element 20 may be provided for electrically heating the vessel.

This construction provides a device in which the temperature of the light-sensitive element 16 can be positively controlled so that it is operated at the most advantageous temperature.

When light or other radiant energy is to be measured by means of a selenium or similar light-sensitive cell, it is advantageous that the whole of the energy falling on the light-sensitive material should be absorbed thereby, and none lost by reflection or diffusion, as the sensitivity is thereby increased.

With this object in view the light-sensitive cell may be constructed as illustrated diagrammatically in Figure 4, in which a substantially closed chamber 21 is coated over the whole of its interior with the light-sensitive material. A small opening 22 is provided to admit the radiation and with this arrangement it is ensured that all the energy entering the chamber is absorbed, because any energy reflected from the surface is subjected to repeated reflection until it is all absorbed.

In this arrangement, the current, which is varied by the variation in resistance of the light-sensitive material, is arranged to traverse the whole of the material, the circuit being established by means of two leading-in wires 23, 24 which are connected to two points on the inner coating spaced apart, for example diametrically opposite one another.

In the construction illustrated in Figure 5 the chamber 25 may be made of metal or other conducting material coated on its inner surface with a layer 26 of light-sensitive material. The aperture 27 by which the light enters the cell is closed by glass, quartz or other material transparent to the radiation which is being used. In this case the current is made to traverse the thickness of the layer or film 26 in a radial direction, one pole of the cell being constituted by the chamber 25 to which a connection 37 is made, and the other by a centrally-disposed

terminal 28 which is led out through a suitable insulating bush. An electrical connection between the inner surface of the layer 26 and the part 28 is provided by filling the chamber with a conducting liquid.

70

In Figure 6 an alternative construction of cell is illustrated in which a thin plate 29 made up of a plurality of crystals of selenium is used as the end wall of a vessel 30. One connection may be made directly to the outside surface of the plate 29, and the vessel is filled with a conducting liquid in which a terminal 31 constitutes the other pole of the cell. The walls of the vessel and the liquid are of course such as to be transparent to the radiation which is being used. A modified construction of such a cell is illustrated in Figure 7, in which the selenium plate 32 constitutes a partition in a vessel separating two bodies of liquid which constitute the electrodes of the cell. The liquid on that side of the partition 32 which is not exposed to the radiation may be any suitable conducting liquid, opaque to the radiation concerned, mercury being an example of a suitable liquid.

85

Figure 8 illustrates yet another construction of cell which is constituted by two plates 33, 34, of glass, quartz or other material transparent to the radiation concerned, mounted closely side by side so as to constitute a thin flat container for a light-sensitive fluid. Suitable electrodes are provided at opposite ends of the cell as shown at 35, 36, for connecting it in circuit. Any of the constructions of cell illustrated in Figures 4 to 8 may be arranged or provided with means for controlling their temperature during working in order that they may be caused to operate over a suitable temperature range in which the maximum sensitivity is obtained and parasitic currents are reduced. Also, the whole or any desired part of the circuits associated with the cell, such for example, as the amplifying devices are preferably also provided with means for maintaining them at a low temperature for the purpose of avoiding or minimizing parasitic currents. The temperature control of the whole apparatus may be effected in any desired manner, for example by enclosing the whole of the apparatus in a suitable chamber whereof the temperature can be controlled.

100

I claim:—

1. A resistance unit variable by the action of light, comprising an opaque insulating hollow body provided with an aperture therein for the passage of light, and having a thin film of light sensitive material deposited on the interior thereof.

120

2. A resistance unit variable by the action of light, comprising an opaque insulating hollow body provided with an aperture therein for the passage of light, and having a thin film of light sensitive material de-

125

120

posed on the interior thereof, and means for controlling the temperature of said body.

3. A resistance unit variable by the action of light, comprising an opaque insulating hollow body provided with an aperture therein, and having a film of light sensitive material deposited on the interior thereof, a transparent member forming a closure for said aperture for permitting passage of light to the interior of said body and for retaining a conducting fluid therein, an electrode extending into said conducting fluid, and an electrical connection to said light sensitive film.

15 4. A resistance unit variable by the action of light, comprising an opaque insulating hollow body provided with an aperture therein, and having a film of light sensitive material deposited on the interior thereof, a

transparent member forming a closure for 20 said aperture for permitting passage of light to the interior of said body and for retaining a conducting fluid therein, an electrode extending into said conducting fluid, a terminal extending through said body and connecting with said light sensitive film, and means surrounding said body for maintaining said film at a temperature within the range of maximum sensitivity.

5. A resistance unit variable by the action 30 of light comprising an opaque hollow body of substantially spherical shape provided with an aperture therein for the passage of light, and having a film of light-sensitive material deposited on the major portion of 35 the interior thereof.

In testimony whereof I affix my signature.
JOHN LOGIE BAIRD.
